UNITED STATES PATENT OFFICE.

EDWARD R. DE LUIZ, OF DETROIT, MICHIGAN, ASSIGNOR TO KELVINATOR CORPORATION, OF WILMINGTON, DELAWARE, A CORPORATION OF DELAWARE.

COMPRESSOR.

1,364,082.

Specification of Letters Patent.

Patented Jan. 4, 1921.

Application filed December 22, 1919. Serial No. 346,586.

To all whom it may concern:

Be it known that I, EDWARD R. DE LUIZ, a citizen of the United States, residing at Detroit, in the county of Wayne and State of Michigan, have invented a certain new and useful Improvement in Compressors, of which the following is a full, clear, and exact description, reference being had to the accompanying drawings.

10 This invention relates to compressors for gaseous fluid particularly such as are used in refrigerating apparatus, and has especial reference to refrigerating apparatus of the domestic type although not necessarily limited thereto. While it is well known that the requirements of all refrigerating machinery are severe, owing to the offensive and corrosive nature of the fluids employed, it is a fact that a device for domestic use has 15 peculiarly severe requirements owing to the irregularity of its use, the lack of skilled or constant attention, and the high pressure to which it is occasionally subjected. Such a device is often left unused for long periods 20 of time, such as during the winter months, yet the demand is made that it shall start instantly and operate perfectly at the end of that time; also owing to temporary vacation of premises, discontinuance of electric current, or for accidental reasons, such apparatus is frequently left idle for extended 25 periods in hot weather as a result of which the refrigerant fluid, which under ordinary operating conditions exists largely in the liquefied state, becomes wholly gasified with the production of internal pressure far beyond those which would normally occur. Notwithstanding these extreme drawbacks, no leakage must occur, either of air inward 30 or of refrigerant outward, and no corrosion must result for otherwise the machine might not run when called on.

One of the most fruitful sources of trouble in previous refrigerating systems has 45 originated at the point where the main driving shaft of the compressor projects through the wall of the casing in which it revolves, since it is at this point that leakage of refrigerant or lubricant fluid, inlet of air, and 50 corrosion of the parts has most frequently occurred. The objects of the present invention are the provision of a compressor of such construction as to overcome and avoid such leakage without such nicety of fit as 55 will impede the operation of the compressor;

the provision of a compressor of such nature and construction as always to remain tight under all conditions of temperature and pressure; the provision of a compressor of such design as to be more easily constructed and assembled than previous devices; the provision of a new and improved construction of sealing and bearing means; the provision of a new and improved expedient for maintaining contact between the 60 parts of such a bearing; while further objects and advantages of my invention will become apparent as the description proceeds.

In the drawings accompanying and forming a part of this application, I have shown certain mechanical constructions in which my inventive idea can be embodied, although it will be understood that this drawing is intended to be merely illustrative and not 70 limiting upon me. In this drawing, Figure 1 represents a longitudinal vertical sectional view through the crank casing of a preferred design of compressor embodying my improvements; Fig. 2 is a detail view illustrating a modified arrangement of the sealing parts.

The particular compressor shown is of the cylinder type and comprises a cylinder block 1 having therein the cylinders 2, 3, and integral therewith the hollow crank-case 4. One end of this crank-case is formed with a hollow boss 5 having a bearing 6 therein while the other end is formed with the aperture 7 to which is bolted a closure plate 8, which carries a bearing-bushing 9. Journaled in these bearings is a crank-shaft 10 that is provided outside the crank-case with a receiving portion 11 adapted to have a pulley, gear, or other operating member secured thereto, and provided inside the crank-case with pitmen 12-12. My invention is not dependent upon the particular type of compressor shown herein, and is equally applicable to those of the rotary type.

At a point between the bushing 9 and attaching portion 11, the shaft 10 is formed with an outwardly facing shoulder 15, and outside of that shoulder with a reduced portion 16 provided with screw threads 105 which are at least as large in diameter as the portion 11; and against the face of the shoulder 15, I secure a bearing ring 18 by means of a nut 19. A gasket 19^a of some soft metal such as lead or copper is pref-

erably inserted between the ring and shoulder.

Loosely surrounding the portion of the shaft inside of said bearing ring is a collar 20 having at least its outer end formed of anti-friction metal as shown at 21 and bearing against the peripheral portion of the ring 18. To the other end of said collar there is hermetically secured a longitudinally-expansible sheath 22 of circumferentially-corrugated, flexible sheet metal, the opposite end of said sheath being hermetically attached to the face of the plate 8 in any suitable manner as by having its margin flared and clamped beneath the ring 23 which is bolted thereto. While I do not limit myself in this regard, I have found the corrugated metal as manufactured by the Fulton Company of Knoxville, Tennessee, to be very satisfactory for this purpose, and for the anti-friction metal 21, I have employed with great success the so-called "genelite" metal or graphite-containing bronze alloy as described and claimed in the application of E. J. Copeland, filed January 31, 1918, Serial No. 214,605. In order to maintain constant contact between the collar 20 and ring 18, I place the former under spring pressure as by the use of a helical spring 25 having one of its ends seated in a recess 26 formed in the outer face of the ring 23 and having its opposite end resting against a split ring 27 mounted in a groove 28 of the collar 20. I have shown the ring 23 and other parts as surrounded by a hollow shield 30, which is the preferred construction, but which has no bearing upon the operation of the device.

In the construction shown in Fig. 1, the shoulder 15 is located at a sufficient distance from the end of the bushing 9 to accommodate the entire sealing mechanism, but in Fig. 2 I have shown a modified arrangement wherein the shoulder 15^a is located very close to said bushing, and the bearing ring 18^a is formed with an internal cylindrical extension or sleeve 18^b of a length sufficient to receive the sealing members, the location of the thread 17 and nut 19 remaining as before. Leakage beneath the ring is prevented by a gasket 19^a. The collar 20^a surrounds the sleeve portion 18^b of the ring, and is here illustrated as made entirely of anti-friction metal such for example as Babbit metal. The sheath 22 is in this instance secured directly to the anti-friction metal, and the same spring 25 and split ring 27 are employed as before.

Owing to the fact that the bearing ring 60 faces inwardly, gas pressure inside the compressor has a tendency to force the collar 20 outwardly, and thereby increase the tightness of the joint, while the location of the spring 25 outside the sheath facilitates the assembly, inspection and repair of the ap-

paratus. When lubricant is employed inside the compressor, sufficient of the same will generally work out between the shaft and bushing 9 to lubricate the sealing ring, although when the same is made of the materials herein suggested, perfect operation can be secured with little or no lubrication. It will be understood, however, that I do not limit myself to the employment of the particular materials herein mentioned and that the embodiments here shown constitute only a small number out of the many constructions in which my inventive idea may be utilized, wherefore I do not restrict myself in any way except as specifically recited in the claims hereto annexed or rendered necessary by the prior state of the art.

Having thus described my invention, what I claim is:—

1. In a compressor, in combination, a casing having an opening and a shaft projecting through said opening and having an outwardly facing shoulder, a bearing ring surrounding the shaft outside of said shoulder and clamped thereagainst, said bearing ring having an inwardly facing peripheral bearing portion, a collar bearing against such peripheral portion, a flexible member hermetically joined to said collar and casing, and a spring forcing said collar toward said ring. 90

2. In a compressor, in combination, a casing having an opening and a shaft projecting through said opening, said shaft having an annular bearing surface spaced apart from and turned toward said casing, a collar surrounding said shaft between said bearing surface and casing, a flexible sheet metal member hermetically joined to said collar and casing, and a spring forcing said collar toward said bearing surface. 100

3. In a compressor, in combination, a casing having an opening and a shaft projecting through said opening and having an outwardly facing shoulder, a bearing ring surrounding the shaft outside of said shoulder and clamped thereagainst, said bearing ring having an inwardly facing peripheral portion, a collar bearing against such peripheral portion, a longitudinally expansible circumferentially-corrugated, flexible sheet metal sheath, hermetically secured to said collar and casing, and a helical spring bearing against said collar and casing. 110

4. In a compressor, in combination, a casing having an opening and a shaft projecting through said opening and having an outwardly facing shoulder, a bearing ring surrounding the shaft outside of said shoulder and clamped thereagainst, said bearing ring having an inwardly facing peripheral portion, a collar bearing against such peripheral portion, a longitudinally-expansible, circumferentially-corrugated, flexible sheet metal sheath, hermetically secured to said 125 130

- collar and casing, and a helical spring surrounding said sheath and arranged to press said collar against said ring.
5. In a compressor, in combination, a casing having an opening, a shaft rotatably mounted in said opening and having an annular outstanding bearing surface spaced from and turned toward said casing, a collar surrounding said shaft between said bearing surface and casing, a longitudinally expandible, circumferentially-corrugated, flexible sheet metal sheath hermetically joined to said collar and casing, and spring means holding said collar against said bearing surface.
6. In a compressor, in combination, a casing having an opening, a shaft rotatably mounted in said opening and having an annular outstanding bearing surface spaced from and turned toward said casing, a collar surrounding said shaft between said bearing surface and casing, a longitudinally expandible, circumferentially - corrugated,
- flexible sheet metal sheath hermetically joined to said collar and casing, and a helical spring surrounding said sheath and holding said collar against said bearing surface.
7. In a compressor, in combination, a casing having an opening, a shaft rotatably mounted in said opening and having an annular outstanding bearing surface spaced from and turned toward said casing, a collar surrounding said shaft between said bearing surface and casing, a longitudinally expandible, circumferentially - corrugated, flexible sheet metal sheath hermetically joined to said collar and casing, said collar having an external groove, a split ring in said groove, and a coil spring having one end embracing and seated against said ring and the other seated against said casing outside of said sheath.

In testimony whereof I hereunto affix my signature.

EDWARD R. DE LUIZ.
